UNITED STATES PATENT OFFICE.

PETER SALAMON, OF PHILADELPHIA, PENNSYLVANIA.

METALLIC RAILROAD-TIE AND FASTENER.

1,373,356.

Specification of Letters Patent. Patented Mar. 29, 1921.

Application filed February 2, 1921. Serial No. 441,833.

To all whom it may concern:

Be it known that I, PETER SALAMON, a citizen of Poland, residing at Philadelphia, in the county of Philadelphia and State of Pennsylvania, have invented certain new and useful Improvements in Metallic Railroad-Ties and Fasteners, of which the following is a specification.

This invention relates to certain new and useful improvements in metallic railroad ties and fasteners and has particular reference to an improved composite tie embodying a main body portion formed with rail seats and having rail fastening means and adapted for removable reception of a secondary plate member so that the latter is held upon the main member or body of the tie by the rails, the body member being adapted for being embedded in ballast or the like with the plate member flush with the upper surface of the ballast or roadway.

Another object of the invention is to provide a railroad tie of this kind which may be reversed when desired so that both the upper and lower portions of the same may be utilized and the life of the tie prolonged.

Other objects will appear as the nature of the invention is better understood, the same consisting in the novel form, combination and arrangement of parts hereinafter more fully described and shown in the accompanying drawings, in which like reference characters indicate similar parts throughout the several views.

In the drawings,

Figure 1 is a side elevational view of a tie constructed in accordance with the present invention, with rails operatively fastened thereon and shown in transverse section,

Fig. 2 is a top plan view of the device shown in Fig. 1,

Fig. 3 is an enlarged fragmentary detail view in longitudinal section upon line III—III of Fig. 2,

Fig. 4 is a transverse sectional view upon line IV—IV of Fig. 2, and

Fig. 5 is an enlarged perspective view of one end portion of the main tie member.

Referring more in detail to the several views, the present invention embodies a main tie member or body 5 including a plate-like connecting member 6 with enlarged ends 7 integral therewith and with reduced extensions 8 projecting from the outer ends of the enlarged portion 7, the portions 6, 7, and 8 being of similar width, while the por-

tions 6 and 8 are of the same thickness and the enlarged portion 7 projects above and below the portions 6 and 8 a similar distance. The upper and lower faces of the 60 enlarged portions 7 are transversely grooved to provide rail seats 9 in which the rails 10 are suitably fastened as by means of clamping plates 11 of the usual angular form with the vertical portions thereof engaging the 65 webs of the rails at opposite sides and with the horizontal portions thereof seated upon the upper faces of the bottom flanges of the rails and upon the upper faces of the portions 7 of the tie at opposite sides of the 70 seats 9. These clamps may be fastened in place by means of stud bolts 12 passing through apertures provided for the same in the horizontal flanges of the plates 11 and threaded into threaded sockets 13 provided 75 in the enlarged end portions 7 at opposite sides of each of the seats 9.

A surface plate member 14 of slightly greater width and length than the bottom member 5 and of about the same thickness 80 as the projecting portions of the enlarged end members 7 is provided with end openings 15 of such a size and shape as to snugly receive the projecting portions of these end members 7 with the remaining greater portions of the plate 14 resting upon the portions 6 and 8 of the tie member or body 5. The plate 14 is thus in the nature of a steadyng element adapted to be only slightly embedded in the ballast or the road- 90 bed, and it is provided with transverse grooves 16 coinciding with the seats 9, which grooves 16 provide further seats for the rails 10. The plate 14 is thus effectively held to the body member 5 of the tie by the rails, 95 and said plate 14 may be disposed upon the projecting portions of the enlarged ends 7 so as to use either the upper or under seats of the body member 5, if desired.

It is believed that the construction and 100 operation as well as the manner of use and advantages of the present invention will be readily understood and appreciated from the foregoing description by those skilled in the art.

105 Minor changes may be made without departing from the spirit and scope of the invention as claimed.

What is claimed as new is:

110 1. A reversible metallic railroad tie including a body member formed of an intermediate connecting plate portion having

integral enlarged end members of similar width and with projecting similar portions extending above and below the plane of the connecting portion and provided with transverse rail seat forming grooves, and a surface plate having end openings for snug reception of the projecting portions of the enlarged ends so as to snugly seat upon the connecting portion, said surface plate being provided with transverse grooves registering with the aforesaid seat forming grooves and adapted to receive rails therein whereby the surface plate is held upon the body member of the tie, and means to fasten the rails in said seats.

2. A reversible metallic railroad tie including a body member formed of an intermediate connecting plate portion having integral enlarged end members of similar width and with projecting similar portions extending above and below the plane of the connecting portion and provided with transverse rail seat forming grooves, a surface plate having end openings for snug reception of the projecting portions of the enlarged ends so as to snugly seat upon the connecting portion, said surface plate being provided with transverse grooves registering with the aforesaid seat forming grooves and adapted to receive rails therein whereby the surface plate is held upon the body member of the tie, means to fasten the rails in said seats, said last named means including clamping plates, said projecting portions of the enlarged end members being provided with threaded sockets, and stud bolts passing through the clamping plates and threaded into the threaded sockets.

3. The combination with a metallic tie body member including an intermediate plate-like connecting member with integral enlarged end members thereon, and projecting portions upon the outer ends of said enlarged end members, of a surface plate having end openings adapted for snug reception of the projecting portions of the enlarged ends of said body member so as to flatly seat upon the upper faces of the connecting portion and the projections, said projecting portions of the end members, and the portions of the surface plate at opposite sides of the projecting portions of the enlarged end members being provided with similar alined grooves, and means to fasten railroad rails within said grooves and to the body member.

4. The combination with a metallic tie body member including an intermediate plate-like

connecting member with integral enlarged end members thereon, and projecting portions upon the outer ends of said enlarged end members, of a surface plate having end openings adapted for snug reception of the projecting portions of the enlarged ends of said body member so as to flatly seat upon the upper faces of the connecting portion and the projections, said projecting portions of the end members, and the portions of the surface plate at opposite sides of the projecting portions of the enlarged end members being provided with similar alined grooves, means to fasten railroad rails within said grooves and to the body member, the enlarged end portions, connecting portion and projections all being of the same width, and the projecting portions of the end members being similar at opposite sides whereby the tie may be reversibly employed with the surface plate securable upon either of the opposite faces of the connecting portion and the projections.

5. The combination with a metallic tie body member including an intermediate plate-like connecting member with integral enlarged end members thereon, and projecting portions upon the outer ends of said enlarged end members, of a surface plate having end openings adapted for snug reception of the projecting portions of the enlarged ends of said body member so as to flatly seat upon the upper faces of the connecting portion and the projections, said projecting portions of the end members, and the portions of the surface plate at opposite sides of the projecting portions of the enlarged end members being provided with similar alined grooves, means to fasten railroad rails within said grooves and to the body member, the enlarged end portions, connecting portion and projections all being of the same width, and the projecting portions of the end members being similar at opposite sides whereby the tie may be reversibly employed with the surface plate securable upon either of the opposite faces of the connecting portion and the projections, and said surface plate being of slightly greater width and length than the body member so as to provide a steadyng element.

In testimony whereof I affix my signature in presence of two witnesses.

PETER SALAMON.

Witnesses:

ALEXIS BURKOVITZ,
PETER KRECKMANN.
